RECEPTACLE FOR HOLDING SMALL TOILET ARTICLES

Filed June 5, 1928

ARTHUR ZADEK
INVENTOR

BY *Otto Munk*
his ATTORNEY.

UNITED STATES PATENT OFFICE.

ARTHUR ZADEK, OF NEW YORK, N. Y.

RECEPTACLE FOR HOLDING SMALL TOILET ARTICLES.

Application filed June 5, 1928. Serial No. 283,106.

My invention relates to a receptacle for holding the small toilet articles of an infant and has reference particularly to a one piece glass base embodying cavities for soap and 5 powder and upright lugs to support a comb and brush.

The invention has for its principal object to provide a receptacle of this character, which is cast in a single piece of glass having 10 smooth surfaces and rounded corners, and which is capable of being sterilized by boiling in water whenever it is found necessary.

A further object of my invention is to afford a cavity in the glass mold for the head 15 or bristles of a brush and also a raised bridge portion to hold the handle of the brush.

I accomplish these objects by means of a construction hereinafter described in the specification and set forth in the claim, and 20 illustratively exemplified in the accompanying drawings, in which, Figure 1 is a perspective view of my improved toilet receptacle showing the toilet articles in position; Figure 2 is a similar view with the toilet articles removed; and Figure 3 is a transverse sectional view taken on lines 3—3 of Figure 2, showing the cavity and bridge for the brush.

Referring to the drawing, 10 denotes the 30 glass base or receptacle which is preferably square in plan and comprises a single casting having a flat top portion 11 and depending marginal skirt portion 12. At the rear of the top 11 two upright U-shaped bridge portions 35 13 project in a direction from front to rear and at spaced distances from each other. The upstanding projections or arms 14 of bridge portions 13 are intended to accommodate the ends of a comb 15 therebetween, as illustrated 40 in Figure 1. Intermediate the top 11 between the front and rear thereof are arranged two cavities 16 and 17, the former being preferably rectangularly shaped while the latter is

round. The bottom of each cavity is below the level of the top 11 and is rounded off at 45 its corners 18 to join the upright side walls 19 which project to an elevation substantially above the top portion 11. The receptacles thus formed are open at their tops and accommodate covers 20 of any suitable material, 50 e. g. celluloid or glass. At the front of the glass base 10, the top 11 is provided with an upstanding U-shaped portion 21 in line with the similar portion 13 on the left side of the rear; this stand 21 is to accommodate the 55 handle of a brush 22, the head or bristles 23 being received in an oval shaped depression 24 on the right of the stand 21 and in front of the round cavity 17. The depression 24 is very much more shallow than the other cavities 60 16 and 17 and it is provided with round corners 25 where its side walls join the bottom 26 and top surface 11, as illustrated particularly in Figure 3.

It will be clear that due to the fact the 65 entire base 10 is cast in a single piece of glass it may be simply placed in boiling water to sterilize and because of the care exercised in its production to provide round corners whenever possible, the danger of foreign substances 70 gathering at the corners is avoided.

Having now described my invention, what I claim and desire to secure by Letters Patent is:

As an article of manufacture, a receptacle 75 for toilet articles comprising a one piece cast glass base having a depending marginal skirt portion, spaced upright U-shaped portions, depressions with upright walls projecting above the base, and an upright U-shaped portion in front of two of said depressions and opposite a third depression which has its side walls flush with the level of the base. 80

In testimony whereof I affix my signature.

ARTHUR ZADEK.
